UNITED STATES PATENT OFFICE.

OLIVER S. GARRETSON, OF BUFFALO, NEW YORK.

DESIGN FOR A BOOK-COVER.

SPECIFICATION forming part of Design No. 22,596, dated July 11, 1893.

Application filed February 13, 1893. Serial No. 462,202. Term of patent 14 years.

To all whom it may concern:

Be it known that I, OLIVER S. GARRETSON, of Buffalo, in the county of Erie and State of New York, have invented and produced a new and original Design for Book-Covers, of which the following is a specification, reference being had to the accompanying drawing, forming a part thereof.

The leading features of my design consist in a border extending down the back edge of the cover and along the lower edge of the same and a field extending therefrom to the front and upper edges of the cover. The portion of the border extending down the back edge of the cover is denoted by A and the portion which extends along the bottom edge of

the cover is denoted by a. The field, is denoted by B. The cover also presents a tip C at the upper front corner. The inner edges of the border and tip are curved thereby imparting to the field B a curved outline where it meets the border and tip and straight outlines where it extends to the front and upper edges of the cover.

What I claim is—

The design for a book cover as herein shown and described.

OLIVER S. GARRETSON.
